US00D886764S

(12) **United States Design Patent** (10) Patent No.: **US D886,764 S**
(45) Date of Patent: ** Jun. 9, 2020

(54) **SPEAKER**

- (71) Applicant: **Lloyd Baggs Innovations, LLC**, Nipomo, CA (US)
- (72) Inventors: **Lloyd R. Baggs**, Nipomo, CA (US); **Daniel Baggs**, Nipomo, CA (US); **Ernesto Quinteros**, Nipomo, CA (US); **Thomas Linn**, Nipomo, CA (US)
- (73) Assignee: **Lloyd Baggs Innovations, LLC**, Nipomo, CA (US)

(**) Term: **15 Years**

(21) Appl. No.: **29/583,888**

(22) Filed: **Nov. 9, 2016**

(51) LOC (12) Cl. **14-01**

(52) U.S. Cl.

USPC **D14/204**

(58) **Field of Classification Search**

USPC D14/167, 168, 170–172, 188, 204, 209.1, D14/210–216, 219, 221, 222, 224; 181/144, 148, 153, 157, 198; 369/6–12; 381/301–303, 306, 332, 334, 336, 345, 381/361–363, 386–388

CPC G06F 1/1688; H04R 1/02; H04R 1/025; H04R 1/026; H04R 1/323; H04R 1/403; H04R 1/2803; H04R 1/2834; H04R 5/02; H04R 9/06; H04R 2201/021; H04R 2400/00; H04R 2400/07; H04R 2499/11

(57) **CLAIM**

The ornamental design for a speaker, as shown and described.

DESCRIPTION

FIG. 1 is a perspective view of a speaker, showing our new design.

FIG. 2 is a front view thereof.

FIG. 3 is a rear view thereof.

FIG. 4 is a side view thereof.

FIG. 5 is an opposite side view thereof.

FIG. 6 is a top view thereof; and,

FIG. 7 is a bottom view thereof.

The broken lines in the figures illustrate the portions of the design that form no part of the claimed design.

1 Claim, 7 Drawing Sheets
